Primary Examiner — Richard E Chilcot(74) *Attorney, Agent, or Firm* — Knobbe, Martens, Olson & Bear, LLP(57) **CLAIM**

The ornamental design for a part of machine for molding and casting nails and screws, as shown and described.

DESCRIPTION

1. Part of machine for molding and casting nails and screws
FIG. 1.1 is a top perspective view of a part of machine for molding and casting nails and screws;
FIG. 1.2 is a bottom perspective view thereof;
FIG. 1.3 is a right side view thereof;
FIG. 1.4 is a left side view thereof;
FIG. 1.5 is a front view thereof;
FIG. 1.6 is a rear view thereof;
FIG. 1.7 is a bottom view thereof; and
FIG. 1.8 is a top view thereof.
